UNITED STATES PATENT OFFICE.

SAMUEL F. ESTELL, OF CHICAGO, ILLINOIS.

CAR-SEAL.

SPECIFICATION forming part of Letters Patent No. 660,850, dated October 30, 1900.

Application filed December 15, 1899. Serial No. 740,896. (No model.)

To all whom it may concern:

Be it known that I, SAMUEL F. ESTELL, a citizen of the United States, and a resident of Chicago, county of Cook, and State of Illinois, have invented certain new and useful Improvements in Car-Seals, of which the following is a specification, and which are illustrated in the accompanying drawings, forming a part thereof.

10 This invention relates to that type of car-seals which comprise a light metal strap adapted to be passed through the fastening of a car-door and to have its ends joined in such manner that they cannot be separated for the 15 purpose of permitting the disengagement of the door-fastening without mutilation.

The objects of the invention are to simplify and cheapen the construction and to obtain perfect security.

20 The invention consists in the arrangement of parts hereinafter fully described, and which are illustrated in the accompanying drawings, in which—

Figure 1 is a plan view of the head of the 25 seal. Fig. 2 is a plan section of the same, the outer cap being removed and the tongue-piece being out of engagement with the case. Fig. 3 is a longitudinal section on the line 3 3 of Fig. 1, and Fig. 4 is a cross-section on the line 30 4 4 of Fig. 1.

The seal is preferably formed of a simple sheet-metal strap A, one end of which is provided with lateral flanges B. A tongue-piece C projects from the same end and is adapted 35 to be overturned upon the body portion, so as to form a hinge-socket for the wire detent D. This detent is made of spring-wire and is folded U shape. Preferably the two arms of the U are bent inwardly intermediate of their 40 ends and at their extreme ends are bent laterally, as shown at d, so as to project perpendicularly from the plane of the U.

A cap-piece E, of sheet metal and of approximately the same length as the flanges B, 45 is superimposed upon the flange portion of the strap, and its edges are turned downwardly and then laterally to form the feet e e. The flanges B are then overturned and pressed down upon the feet e e, thereby securing the 50 cap-piece E in place. The rearward end of the chamber of the head thus formed is closed by a projecting end F of the cap E, which is

folded downwardly and inwardly before the cap is secured in place. A recess is formed transversely across the inner face of the cap 55 E, as shown at G, by striking up the metal, this recess accommodating the ends d of the detent-spring.

The opposite end of the strap A is given the form of an arrow-head, as shown at H, 60 and when being inserted under the cap E will by its point force apart the ends d d of the detent, so as to pass between them, these ends falling behind the barbs of the arrow-head, thereby effectually preventing the withdrawal of the strap end from the head of the seal. The depth of the chamber of the seal-head is substantially equal to the thickness of the strap and of the wire forming the detent D, so that when the arrow-head end of 70 the strap is inserted within this chamber it so completely fills its open end that it is impossible to insert thereinto a bolt for the purpose of spreading the detent ends e e in order to release the seal, and hence the seal can- 75 not be separated except by being destroyed.

The transverse recess formed in the cap at G for the accommodation of the ends d of the detent is so located that its front wall forms a bearing for such ends when withdrawing 80 strain is applied to the strap, thereby preventing the wire from being distorted.

I claim as my invention—

1. In a car-seal, the combination with a strap having a chambered head at one end, 85 the outer end of such head being open, the farther end of the strap being pointed and barbed, of a spring-wire detent in substantially U form and secured by its cross member within the chamber of the head, both of 90 its arms being free, the ends of such detent being substantially perpendicular to the face of the strap, whereby the barbed end of the strap may enter between such ends and engage with both of its barbs. 95

2. In a car-seal, the combination with a strap having a chambered head at one end, the outer end of such head being open, the farther end of the strap being pointed and barbed, of a spring-wire detent in substantially U form and secured within the chamber of the head, the ends of such detent being substantially perpendicular to the face of the strap, one wall of the head having an in-

ternal transverse recess adapted to receive such detent ends.

3. In a car-seal, in combination, a strap having one of its ends formed as an arrow-head and having at its opposite end lateral flanges and an inturned tongue-piece, a **U**-shaped wire spring secured under such tongue and being adapted to lie along the face of the strap and having its ends upturned so as to

10 be perpendicular thereto, a cap-piece having its side ends bent downwardly and laterally

to form feet adapted to rest upon the lateral flanges of the strap and having a transverse recess for receiving the upturned ends of the wire and an inturned tongue at its rearward 15 end, the edges of the flanges of the strap being overturned upon the feet of the cap.

SAMUEL F. ESTELL.
